UNITED STATES PATENT OFFICE.

WILLIAM PEARSON, OF HOT SPRINGS, ARKANSAS.

COMBINATION-TOOL.

1,074,380.

Specification of Letters Patent. Patented Sept. 30, 1912.

Application filed May 9, 1912. Serial No. 696,228.

To all whom it may concern:

Be it known that I, WILLIAM PEARSON, a citizen of the United States, residing at Hot Springs, in the county of Garland, 5 State of Arkansas, have invented certain new and useful Improvements in Combination-Tools; and I do hereby declare the following to be a full, clear, and exact description of the invention, such as will enable 10 others skilled in the art to which it appertains to make and use the same.

This invention is directed to improvements in wire working tools, and has for its object to so construct a tool of this character 15 with a maximum number of parts for different uses, and so arranged that a compact combination tool is produced.

A further object of the invention is to produce a tool consisting of a number of 20 hand operated tools in a single instrument of convenient size.

With these and other objects in view, this invention resides in the novel features of construction, formations, combinations and 25 arrangements of parts to be hereinafter more fully described, claimed and illustrated in the accompanying drawings, in which:—

Figure 1 is a side elevation of the tool. Fig. 2 is an edge view of the same. Fig. 3 30 is a sectional view on line 3—3 of Fig. 1. Fig. 4 is an end view of the tool. Fig. 5 is a perspective view of the wire stretching yoke holder. Fig. 6 is a detail perspective view of the stretching yoke.

Referring to the drawings, the numerals 35 1 and 2 designate a pair of handles which are crossed adjacent their forward ends and pivoted at their point of crossing. The handles 1 and 2 are formed with circular enlargements 3 and provided at opposite points with wire receiving notches 4 and 5, said notches being adapted to register when the handles are in a slightly open position, and when the handles are drawn together the 40 wire between the notches will be cut.

The enlargement 3 carried by the handle 1 has formed integral therewith a jaw 6, said jaw having its inner face serrated as at 7, the opposing face of the jaw 8 is also serrated as at 9. The jaw 8 is formed integral 45 with the enlargement 3 carried by the handle 2. The jaw 8 is provided with a pair of extensions 10, said extensions having their inner faces, one of which is serrated as at 11 beveled, and forming a rigid jaw for engaging nuts or pipes as desired. The jaw 8 ter-

minates in a hammer head 12, and is further formed adjacent the serration 7 with a V shaped notch 13, said notch being adapted to confront a similar notch formed upon the face of the jaw 8 so that nuts of various sizes may be engaged.

Formed rearwardly of the serrations 7 and 9 upon the jaws 6 and 8 are toothed depressions 14 which are adapted, when confronting to firmly hold a bolt. Formed rearwardly of the depressions 14 and in the opposing faces of the jaws are semi-circular grooves 15, the groove upon the jaw 6 opening into a groove 16 formed upon one side 18 of the said jaw and terminating in a groove 17 formed upon the outer face of the said jaw, said groove being used in splicing wires. The ends of the jaws 6 and 8 are both provided with V-shaped notches 18, the resultant projections 19 serving to extract staples from fence posts. The inner end of the handle 1 is formed with a semi-circular enlargement 20 which forms a fulcrum for the claw bar 21, and is especially adapted for use in removing nails, and to open boxes. The handle 2 terminates in a point 22, which serves as a screw driver. Each circular enlargement 3 carried by the handles 1 and 2 is provided with a perforation 23, said perforations when in registry are adapted to receive a shank 24 of a yoke holder 25, the said shank having its upper ends squared as at 26 so as to engage the squared portion of the perforation 23 formed in one of said enlargements, thus preventing independent rotation of the holder 25. The holder 25 is held against accidental displacement by a cotter pin 27 which is passed through a perforation formed in the lower end of the shank. Extending longitudinally of the holder 25 is a longitudinal groove 28, which opens into a slot 29 formed in one side of said holder.

The wire stretching yoke 30 is formed 100 from a single length of metal, and has the outer ends of its arm 31 formed with hooks 32 for detachably engaging the wire fence fabric when it is desired to stretch the same and to hold it in its stretched position before the same is finally secured to the fence post. The lower ends of the arms 31 terminate in parallel portions 33 and 34 connected by a transversely disposed arm 31. The portions 33 are formed with downward inclined sides 35 which result in shoulders 36, said shoulders being slightly

rounded so that the arm 34 is permitted to freely pivot in the groove 28 formed in the holder 25. By forming the inclined sides 35 in the portions 33, either one of said portions may be inserted in the groove 28 of either side of the holder 25, the slot 29 permitting the free passage of either one of the portions 33.

When it is desired to use the tool as a wire stretcher it is only necessary that the yoke 30 be connected to the holder 25, and the jaws 6 and 8 placed against the fence post and at which time the hooks 32 of the yoke are engaging the wire fabric, whereupon pressure being applied to the handles, the wire may be stretched to the desired tension.

What is claimed is:—

1. A tool of the class described comprising a pair of handles having formed near their outer ends circular enlargements, perforations formed centrally thereof, one of the perforations having a squared portion, a shank engaged in the perforations, said shank having a yoke engaging holder, a squared portion formed upon the shank for engaging the squared portion of one of the perforations, said holder having a lon-

gitudinal groove formed longitudinally therefor for detachably connecting the 30 yoke.

2. A tool of the class described comprising a pair of handles having circular enlargements formed at their inner ends, perforations formed centrally thereof for registry, one of said perforations having a squared portion, a yoke holder, a shank therefor having a squared portion for engaging the squared portion of said perforation, said shank being adapted to pivotally connect the handles, said holder having a longitudinal groove formed therein, a slot opening into the groove, a wire stretching yoke having parallel portions formed with inclined sides to produce shoulders, 45 said portions being connected by an arm adapted to rest in the groove after one of said portions has been passed through the slot.

In testimony whereof, I affix my signature, in presence of two witnesses.

WILLIAM PEARSON.
